UNITED STATES PATENT OFFICE.

CARL F. DRURY, OF CLEVELAND, OHIO, ASSIGNOR TO THE CLEVELAND FOUNDRY COMPANY, OF CLEVELAND, OHIO, A CORPORATION OF OHIO.

DESIGN FOR A WINDOW-SETTING FOR STOVES.

SPECIFICATION forming part of Design No. 37,092, dated August 16, 1904.

Application filed July 12, 1904. Serial No. 216,298. Term of patent 7 years.

To all whom it may concern:

Be it known that I, CARL F. DRURY, a citizen of the United States, residing in Cleveland, in the county of Cuyahoga and State of Ohio, have invented a new, original, and ornamental Design in Window-Settings for Stoves, reference being had to the accompanying drawings, forming a part thereof.

As shown in the drawings, Figure 1 is a plain front elevation of the design. Fig. 2

is an edge elevation thereof, and Fig. 3 is a top or plan view thereof.

What I claim as new, and desire to secure by Letters Patent, is—

The ornamental design for a window-setting for stoves, as shown. 15

CARL F. DRURY.
